UNITED STATES PATENT OFFICE.

GEORGE W. BLAIR, OF PITTSBURG, PENNSYLVANIA.

DESIGN FOR A LAMP-CHIMNEY.

SPECIFICATION forming part of Design No. 26,004, dated September 8, 1896.

Application filed May 16, 1896. Serial No. 591,384. Term of patent 14 years.

To all whom it may concern:

Be it known that I, GEORGE W. BLAIR, of Pittsburgh, in the county of Allegheny and State of Pennsylvania, have invented a new and original Design for Lamp-Chimneys, of which the following is a full, clear, and exact description.

The design consists in a lamp-chimney having on the exterior surface, opposite the position of the light, a raised or sunken pattern composed of closely-adjacent figures, and having on the interior a similar pattern in reverse, substantially as herein shown and described.

The essential feature of my design is the application of such pattern to the part of the chimney on the inside surface as well as the outside surface of the glass opposite to the light or burner of the lamp.

As shown in the drawings, the chimney has on its exterior surface a pattern 2, composed of series of closely-adjacent raised or sunken figures, which give to the chimney a beaded appearance, and, as illustrated by the sectional Figure 2, which is drawn on a larger scale than Fig. 1, the interior surface of the chimney is similarly figured, but in reverse.

I claim -

The design for a lamp-chimney substantially as herein shown and described.

In testimony whereof I have hereunto set my hand.

GEORGE W. BLAIR.
